UNITED STATES PATENT OFFICE

163,609

BOTTLE CARRIER

Charles E. Jones, Chicago, Ill., assignor to General American Transportation Corporation, Chicago, Ill., a corporation of New York

Application June 30, 1950, Serial No. 10,901

Term of patent 14 years

(Cl. D58—13)

To all whom it may concern:

Be it known that I, Charles E. Jones, a citizen of the United States, residing at Chicago, county of Cook, and State of Illinois, have invented a new, original, and ornamental Design for Bottle Carrier, of which the following is a specification, reference being had to the accompanying drawing, forming a part hereof.

Fig. 1 is a front elevational view of a bottle carrier, showing my new design;

Fig. 2 is a plan view of the carrier;

Fig. 3 is an end elevational view; and

Fig. 4 is a cross sectional view taken along the line 4—4 of Fig. 1, looking in the direction of the arrows.

The designs shown on the front in Fig. 1 and

on the end in Fig. 3 are repeated on the back and other end of the carrier respectively.

I claim:

The ornamental design for bottle carrier, as shown and described.

CHARLES E. JONES.
